UNITED STATES PATENT OFFICE.

HARRY MINTZ, OF BOSTON, MASSACHUSETTS.

COUCH HAMMOCK.

Application filed June 14, 1924. Serial No. 720,007.

This invention pertains to couch hammocks or swing couches and more particularly to a type of hammock especially adapted for use indoors, for example in sun parlors and the like, where the usual means provided for suspending couch hammocks or the like are unsuitable.

Principal objects of the invention are to provide a swing couch or couch hammock adapted to be set up in any convenient location and embodying in its own structure the necessary supports for suspending the swinging seat, thus avoiding the use of unsightly suspension stands or frames or the necessary 10 means of providing hooks or other attaching means in the walls or ceiling of the apartment, but without unduly restricting freedom of motion of the swinging seat; to provide a swing couch of knock-down type having 15 separable parts adapted to be packed snugly for shipping or storage but which are held securely and rigidly in operative relation when set up; to provide means for connecting the several parts of the swing couch 20 of such a character that the parts may be assembled or separated easily and without the use of tools; and to embody the invention in a durable structure of pleasing appearance which may be manufactured readily 25 and at relatively low cost.

In the accompanying drawings, a preferred embodiment of the invention is illustrated by way of example, and in such drawings.

Fig. 1 is a perspective view of the device set up for use but omitting the usual mattress and cushions;

Fig. 2 is a fragmentary front elevation to large scale illustrating the means for connecting one of the end frames to one of the longitudinally extending rails which hold the end frames in spaced relation;

Fig. 3 is a plan view of the parts shown in Fig. 2;

Fig. 4 is a fragmentary end view of the lower part of one of the brackets secured to the swinging seat and by means of which the latter is connected to the suspending means;

Fig. 5 is a front elevation of the parts shown in Fig. 4;

Fig. 6 is a fragmentary elevation of one end of one of the suspension chains showing the detachable connecting means carried thereby; and

Fig. 7 is a fragmentary perspective view

showing a rear corner of the seat frame and illustrating one of the sockets in which the back rest is removably mounted, a portion of the back rest being shown in position to enter the socket.

In that embodiment of the invention herein selected for illustration the device comprises spaced substantially I-shaped end frames of like construction, each frame having a horizontal elongate foot 1 adapted to rest upon the floor, a top bar 2 substantially parallel to the foot, and a vertical standard connecting the foot and top bar. The vertical standard of each end frame preferably 65 comprises substantially parallel spaced vertical bars 5 and 6, preferably tubular, which diverge from each other at their lower ends to provide substantially horizontal portions 7 and 8 respectively which are secured by 70 means of rivets 9 and 10, or in other suitable manner to a vertical flange 3 constituting a portion of the corresponding foot 1. For convenience in construction, the foot 75 consists of a piece of angle bar having its vertical flange at the outer side of the end frame, and horizontal portions 7 and 8 of the rods 5 and 6 are disposed within the angle of the bar and secured to the inner face of its vertical flange.

The bars 5 and 6 also diverge from each other at their upper ends to provide horizontal portions 11 and 12 respectively, secured by rivets 13 and 14 to the vertically depending flange 4 of the corresponding top 85 bar 2. The latter member likewise preferably consists of a length of angle bar having its vertical flange directed downwardly and at the outer side of the end frame, and the members 11 and 12 are disposed within the 90 angle of the bar so that they are concealed from the outer side of the end frame.

The top bars 2 constitute supports for arm rests 15. The latter are preferably of upwardly convex contour, preferably though not necessarily, hollow for the sake of lightness, and may be made of any suitable material such for example as wicker work or the like.

Each of the bars 5 and 6 of each end 105 frame is provided near the lower part of its vertical portion with a bracket 16 (Figs. 2 and 3). Each bracket comprises a web 17 constituting the outer wall of a chamber 18. Each web 17 is furnished with a vertical slot 19 leading into the chamber 18, such slot being widened midway its length

as indicated at 20 to provide a socket opening leading into the chamber.

The end frames are held in properly spaced relation by means of a pair of rigid 5 rails 21. These rails are disposed in the same horizontal plane and each rail is provided at each end with a bracket member 22 having a rib 23 adapted to fit snugly in the vertical slot or recess 19 in the web 17 10 and also having a button or head 24 at the lower end of the rib 23 adapted to enter the chamber 18 through the socket opening 20 and to be positioned at the lower part of said chamber behind the web 17 so 15 as detachably to connect the rail 21 to the end frame.

The space between the vertical portions of the bars 5 and 6 may preferably be filled in by means of a panel 25. This panel may be 20 of any suitable construction, such for example as wicker work or sheet steel, perforated if desired to simulate such wicker work, or in fact of any other desirable or ornamental construction or appearance. Obviously this 25 panel may be omitted if desired, and the space between the bars 5 and 6 may be left entirely open, or closed, or partially closed in some other manner.

The top bars 2 are provided with openings 26 and 27 or equivalent elements in their opposite ends, preferably in the depending vertical flanges 4 thereof. Suspension members 28, herein illustrated as chains are secured at their upper ends in the several 35 openings. While chains make desirable suspension members, it is contemplated that other and equivalent means may be substituted. Each of these chains terminates in a connecting member at its lower end for 40 a purpose hereinafter described.

The swinging seat or mattress supporting frame S is preferably of substantially rectangular form comprising a front rail 29, end rails 30 and 31 respectively, and a rear rail 32. These rails are preferably of angle bar construction having their horizontal flanges at the bottom and directed inwardly, such flanges being provided with openings 45 to facilitate attachment of the usual spring fabric constituting the support for the mattress or cushions.

At each corner of the seat a vertically extending bracket, preferably of angle iron, is secured thereto. Each of these brackets 55 comprises a flange 33 secured to the corresponding front or back rail of the frame, and an end flange 34 secured to one of the end rails of the frame. At the lower end of the end flange 34 of each bracket, a vertically 60 extending slot 35 is provided, such slot being preferably open at its lower end. This slot is adapted to co-operate with the connector element above described carried by the lower end of the corresponding chain 65 28. This connector element is preferably of

T-shape, comprising a narrow shank 36 and a head 36^a. The shank is of a width permitting it to slip within the slot 35 while the head is of sufficient width to prevent its withdrawal from the slot. With this arrangement it is an easy matter detachably to connect the lower end of each chain to the corresponding bracket. 70

The two rear brackets project upwardly 75 above the plane of the seat frame and short sections of angle iron comprising flanges 37 and 38 are secured to the upper parts of such projecting portions of the brackets in such manner that the flanges 38 of such sections are parallel to the flanges 33 of the brackets. 80

Other short sections of angle iron having flanges 39 and 40 are disposed between the flanges 33 and 38, the flange 40 being horizontal and constituting the bottom of a socket 41 thus provided at the upper end of 85 the bracket. The sockets 41 in the opposite end brackets are adapted removably to support a back rest B comprising a top rail 44, bottom rail 44^a, and end rails 45 and 46 respectively, the lower ends of the end rails 90 being adapted to seat within the respective sockets 41.

If desired the back rest may also comprise longitudinally extending wires 47 secured at one or both ends by means of springs 48 to the end rails 45 and 46 of the back rest and connected to each other if desired and to the top and bottom rails of the back rest by means of springs 49. This back rest may be ornamenteally finished or upholstered if 95 desired with any suitable material or may merely constitute a frame for supporting a removable cushion or cushions. 100

With the construction illustrated it is possible to remove the back rest and seat frame 105 and then to detach the end frames from the connecting rails 21 thus permitting the entire structure to be packed snugly for shipment. At the same time the device may be set up in a very short time without the use 110 of tools and without special directions or skill.

While the mode herein shown of attaching the flexible supports 28 to the lower ends of the brackets 33 is desirable, it is to be understood that other and equivalent connections, for example hooks, bolts, etc., may be substituted without departing from the spirit of the invention. It is also to be understood that the specific mode of connecting 115 the rails 21 to the end frames is not essential to the main purpose of the invention nor are the structural materials above described necessary to its proper embodiment.

The device herein illustrated and claimed 120 is of pleasing appearance and can be set up in any desired location without reference to the necessity for providing suspension means for the swinging seat. The latter is 125 free to swing to the desired extent without 130

interference with the rails 21 connecting the end frames while the employment of the downwardly projecting brackets for attaching the lower ends of the flexible connectors 5 permits the seat to swing in a relatively long arc. Moreover, when the device is set in an exposed situation the back rest may be removed and laid face down upon the seat, thus constituting a protecting cover for the 10 latter when not in use.

The hammock as described may be constructed cheaply and rapidly as the materials employed are in large measure of standard form while the device is extremely 15 durable and capable of hard usage without becoming loose in its joints.

I claim:

1. A couch hammock comprising spaced end frames, a seat frame having a downwardly projecting bracket at each corner, said brackets having vertically elongate slots 20 at their lower ends, the slots being open at their lower extremities, a pair of flexible suspension members carried by each end frame, and a T-shaped connector attached to each suspension member, said connectors being constructed and arranged to have their shank portions engaged in the slots of the 25 respective brackets thereby detachably to

secure the seat frames to the suspension 30 members.

2. A couch hammock having an I-shaped end frame, the top and bottom members of said frame consisting of angle bars having opposed vertical flanges disposed in the same 35 plane and a standard uniting said top and bottom members, said standard comprising a pair of parallel bars having their upper and lower ends bent divergently to provide horizontal members, and means securing the 40 horizontal end members of said bars to the top and bottom bars within their angles respectively.

3. A couch hammock provided with an end frame comprising a horizontal top rail 45 having a downwardly directed vertical flange, a pair of bars provided with horizontal portions secured respectively to said flange, said bars also having vertical portions substantially parallel with each other, 50 the lower ends of said bars being divergently curved to provide horizontal end portions, and a horizontal foot member to which the lower end portions of said bars are attached.

Signed by me at Boston, Mass., this 55 day of June 1924.

HARRY MINTZ.
